UNITED STATES PATENT OFFICE.

MYRTON E. REAM, OF CHICAGO, ILLINOIS.

CHILD'S TOILET-SEAT.

1,304,095.

Specification of Letters Patent.

Patented May 20, 1919.

Application filed May 27, 1918. Serial No. 236,779.

To all whom it may concern:

Be it known that I, MYRTON E. REAM, a citizen of the United States, residing at Chicago, in the county of Cook and State 5 of Illinois, have invented certain new and useful Improvements in Children's Toilet- Seats, of which the following is a specification.

This invention relates to an improved 10 toilet seat for small children, and the object of the invention is to provide means by which such a seat may be quickly and securely mounted on a standard toilet seat and which is arranged to be quickly folded 15 into compact position for storage or transportation.

In the accompanying drawings, Figure 1 is a vertical front-to-rear section, and Fig. 2 is a transverse section showing a seat embodying my invention mounted upon a standard fixture.

In the drawings, 5 indicates a closet bowl and 6 the usual wooden seat thereon. My improved device comprises a base or seat 25 portion 7 having a hole of smaller dimensions than the one in the seat 6. The base 7 is arranged to be secured in place on the seat 6 by means which is secured to the lower side of said base and which depends through 30 the opening in the seat 6 and engages beneath the edges of the latter opening. Said means in the form herein shown comprises a rod 8 having its mid-portion secured to the underside of the base 7 rearwardly of 35 the opening therein in such a manner that the rod may turn in its bearings. Suitable means such as staples 8^a may be employed to secure the rod in place. The end portions of the rod are offset and are sloped down- 40 wardly to engage beneath the seat 6.

In associating the device with the seat 6 the hooked end portions of the rod 8 are passed through the mid-portion of the opening in the seat 6, the rod 8 being moved by 45 gravity into operative position. The base 7 is then moved rearwardly during which movement the inclined ends of the rod 8 will frictionally bind against the edge of the opening in the seat 6 so that the base 7 50 will be firmly secured in place.

To remove the device from the seat 6 the device is simply drawn forwardly. When

the hooked rod 8 is disengaged from the seat 6 the rod may be turned to bring the angular ends closely along the lower face 55 of the seat 7 so as to further reduce the space required for storage of the device. This foldable feature is important to the manufacturer because it reduces the size of the package to be shipped and also lessens liability of damage to the parts by rough handling in shipment.

Spaced above the base 7 is a suitable guard which may be in the form of a U-shaped frame 9 providing side-arms and a 65 back to partially surround the child. This guard frame is connected to the base 7 by means of suitable links or braces 11 at three places which are so arranged that the guard and links may be collapsed to lie closely on 70 top of the seat 7. This collapsible upper structure forms the subject matter of my Patent No. 1,267,590, issued May 28th, 1918.

I claim as my invention:—

1. A child's toilet seat comprising a base 75 adapted to be set upon an ordinary toilet seat, and a device mounted on said base at one end thereof and adapted to depend through the opening in the main toilet seat and engage beneath the latter, said device 80 being disengageable from the seat by a movement of the base relative thereto.

2. A child's toilet seat comprising a base adapted to be set upon an ordinary toilet seat, and a member pivotally mounted on 85 said base and depending therefrom and arranged to pass through the opening in the main toilet seat and engage beneath the opposite edges thereof, said member being adapted to collapse alongside said base when 90 not in use.

3. A child's toilet seat comprising a base adapted to be set upon an ordinary toilet seat, and a rod having its mid-portion pivotally secured to the lower face of said base, 95 the end portions of said rod being offset downwardly and inclined and adapted to be passed downwardly through the opening in the main seat and engage beneath the edges of the latter.

In testimony whereof, I have hereunto set my hand.

MYRTON E. REAM.
